UNITED STATES PATENT OFFICE.

OTTO S. MARCKWORTH, OF COLUMBUS, OHIO.

ORNAMENTAL INLAID WORK.

Application filed July 30, 1926. Serial No. 126,082.

This invention relates to improvements in ornamental inlaid work and consists of an article and the method of making said article.

5 The invention comprehends, essentially, in respect both to the article and the method of making a design wrought in metal in the form of wire stampings or small bars to constitute the tracery of the design and of wood veneers 10 upon one of which such wire frame is placed and upon which the other veneer is positioned, the veneers being properly treated to cause them to adhere to each other and to the wire design frame; and further in dressing off the 15 surface of the upper veneer to cause the tracery of the design to show through and be observable to the eye, while the remainder of the veneer is imbedded or inlaid in the depressions between the lines of the tracery; 20 and also, in some cases, in likewise dressing off the lower veneer so as to expose the design through it as well as through the upper veneer.

Such, in general terms, in a statement of 25 my article and the essential steps of the method of producing it.

In the accompanying drawings, Figure 1 is a plan view of a wire-frame design typical of this element of the article.

30 Figure 2 is a plan view of a piece of wood veneer.

Figure 3 is a similar view of a sheet of celluloid.

Figure 4 is a diagrammatic view representing a hydraulic press on the lower platen of which are laid the elements which are to be treated and to result in my inlaid article.

Figure 5 is a like view showing the addition of an upper cushion or pad laid on the upper veneer.

Figure 6 is a plan view of the completed article or product.

The first step in the method of producing my improved article, and what may be regarded as the first element of the article to be produced, is shown in Figure 1 in skeleton form and re-appears in the completed article as shown in Figure 6.

50 This element constitutes a frame indicated at 2, and formed of wire or a narrow fine bar, the cross section being circular, rectangular or otherwise as may be desired, and the frame being made of one piece bent into such configuration as will depict the desired design. 55 In the illustration shown the design consists of parallel sides and ends with open square

corners 3 and an inner elliptical figure 4. The latter is suspended between the sides and the end bars by pins 5 of wire smaller in diameter than that used in making the design 60 frame.

This frame is to be imbedded between two veneers such as indicated at 6 in Figure 2. This veneer is first treated in a manner to make it pliable and in a degree soft, preferably by the method set forth in application Serial No. 126,081, filed on the 30th day of July, 1926. In said application or patent the wood veneer is preferably treated to a bath of water, glycerine and gelatine and dried so 70 as to leave the wood more or less impregnated with the preparation. It is then treated to a bath of butyl alcohol, etc. as authorized in application Serial No. 126,012 filed on the 30th day of July, 1926.

75 In Figure 3 is illustrated a sheet 7 of celluloid which is the preferred form of plastic material which is to be used in this present method. The celluloid is left dry and is acted upon to render it superficially adhesive 80 by the vapor of the solvent-impregnated veneers on both of its faces.

By observing Figure 4 it will be seen that there is an upper veneer and a lower veneer each indicated at 6 with the celluloid sheet 7 intervening and the design frame generally indicated at 2 placed between the lower veneer and the celluloid; and that there is also a pad or cushion, say of soft wood or cardboard or even of strong blotting paper, indicated at 8 in Figure 4.

These parts are positioned on the lower platen 9 of a hydraulic press having an upper platen 10. When the platens are brought sufficiently together to make the upper one 95 contact with the veneer 6 and pressure is applied, say one thousand pounds per square inch, with or without heating the platens, the veneers will be pressed against the design frame and the latter will be imbedded in the 100 veneers. Those portions of the veneers which underlie and overlie the tracery or bars of the design will be shattered or partially disintegrated, while those portions of the veneers which are opposite the spaces within 105 the lines of the design will be inlaid. The celluloid, under such pressure and due to the superficial action of the solvent becomes strongly adhesive on both faces, but retains its continuity and characteristic toughness, thereby strengthening the unified structure 110 and effecting the permanent adherence of

the veneers to each other and to the skeleton design frame.

In Figure 5 the same lamination is shown as in Figure 4 with the exception that in Figure 5 an upper pad 11 has been added, which is preferable. After the pressing step, with or without heat, has been performed, then the veneers are dressed off smooth, the upper veneer being dressed to a depth sufficient to remove all of its thickness, the shattered parts above the design tracery in particular, to expose the design and leave the veneer imbedded or inlaid around the tracery. And the lower veneer may also be dressed off to the same extent, in which case the product will have a double face, both faces showing the design through the inlaid veneers.

In Figure 6 I have shown the product thus produced, the frame, as indicated at 2, 3, and 4 constituting the design showing through the veneer and the fields *a*, *b*, *c* and *d* indicating the inlaid veneer. The separate wires 5 are imbedded between the veneers and do not come to view because they form no part of the design in the present instance.

Thus it will be seen and understood that my product is a composite one, consisting of an open-work or skeleton frame of metal and a veneer above and below the frame or on both sides thereof; with the veneer on one or both sides removed sufficiently to expose the design and leave the remaining portions of the veneer inlaid in the spaces surrounding the tracery of the design.

This product is not only ornamental in itself and capable of many uses, such as for electric push button plates, name plates, radio casing panels, etc., but is also capable of being bent or curved into different shapes due to the treatment given the veneers and to the bendability of the wire-like design-frame.

It will further be observed that my method of producing this article consists, essentially, of the following steps: That of fabricating the wire-like design frame; that of treating the veneer in the manner stated or in some such equivalent manner; that in treating the celluloid sheet in the manner stated or similarly; that of placing the design-frame on one of the veneers with the other veneer on top of the frame, with the celluloid or other appropriate adhesive intervening; that of pressure, with or without the accompaniment of heat, to imbed or inlay the veneers in the design and shatter the veneers where they overlie the tracery; and that of subsequently dressing off or removing the surplus of the veneers, to the extent of removing so much of one or both of the veneers as is necessary to leave the design exposed so as to show through the wood and to leave also the veneers inlaid in the spaces around the tracery.

It will be understood that I desire to com-

prehend within my invention such modifications as may be necessary to adapt it to varying conditions and uses.

Having thus fully described my invention, what I claim as new and desire to secure by Letters Patent is:

1. An article of the character described, consisting of a design-frame of wire-like formation, the thin bars thus formed constituting the tracery of the design, and a wood veneer forming a body within which such design frame is embedded, the material of the veneer being removed at places over the tracery formed by such frame, and the remainder of the veneer occupying spaces bordering the tracery, and a suitable adhesive applied between frame and veneer to maintain their union.

2. An article of the character described, consisting of a design-frame of wire-like formation, and wood veneers, one on each side of such frame, and an adhesive between them to bind them together, one veneer having its face dressed off to expose said design frame; with the remainder of the veneer occupying the spaces bordering the frame.

3. An article of the character described, consisting of a design-frame of wire-like formation, and two veneers one on each side of the frame, with an adhesive between the veneers, both veneers being dressed off to expose the design frame on both sides, while the remainder of both veneers remains in the spaces bordering the frame.

4. The herein described method of making said article of manufacture, consisting in fabricating a design-frame of wire-like formation to constitute the tracery of the design, in embedding such frame within a veneer of wood by pressure applied to them; in placing an adhesive on the parts to bind the wood and the tracery together; in removing those portions of the wood which overlie the tracery of the design to expose it to view, and in leaving in the depressed spaces bordering the tracery the remainder of the wood of the veneer.

5. The herein described method of making said article of manufacture, consisting in fabricating a wire-like design-frame, in treating sheets of veneer in a solvent solution tending to soften and toughen them; in placing said design-frame and a sheet of celluloid between two such sheets of veneer; in subjecting the composite structure to pressure and heat sufficient in time and degree to inlay the wood of both veneers into the spaces surrounding the tracery of said design; and to shatter the wood at the places opposite the tracery and in dressing off both veneers to expose the design through them.

In testimony whereof, I affix my signature.

OTTO S. MARCKWORTH,
